UNITED STATES PATENT OFFICE.

HENRY J. WIEGAND, OF MILWAUKEE, AND HORACE N. PACKARD, OF WAUWATOSA, WISCONSIN, ASSIGNEES TO THE CUTLER-HAMMER MFG. CO., OF MILWAUKEE, WISCONSIN, A CORPORATION OF WISCONSIN.

CONTROLLABLE RESISTANCE DEVICE.

Application filed November 2, 1923. Serial No. 672,329.

This invention relates to improvements in controllable resistance devices, and more particularly to devices to provide and control relatively high resistance values.

5 In a co-pending application of Henry J. Wiegand, filed July 18, 1923, Serial No. 652,462 is disclosed and claimed an invention and improvement in devices of such character and the present invention has among its 10 objects that of otherwise and further improving such devices.

Another object is that of providing a controllable resistance device whose operative characteristics may be more readily and accurately predetermined and controlled.

Another object is that of providing such a device wherein provision is made for increased facility of circuit connection and physical support thereof.

20 Other objects and advantages will hereinafter appear.

In accordance with the teaching of said co-pending application, an insulating disk or its equivalent having a peripheral conductive coating of high resistance is mounted for rotation with reference to a relatively fixed brush of graphite or other suitable and relatively soft conductive material, said conductive coating having its continuity interrupted at a limited region and having, adjacent such region, an electrical connection with its mounting and operating shaft or with an equivalent conductive element located substantially axially of the disk and 30 making contact with a fixed conductive supporting element or part provided with a suitable circuit terminal.

This arrangement provides, during service, for some degree of restoration and also 40 accretion of material of the conductive coating by means of material of the brush, thereby compensating for possible loss of such coating material as a result of rubbing by the brush or other cause. Also some degree of roughening of the surface of the insulating disk is contemplated, whereby the conductive coating may be originally applied, as 45 well as restored, by simple rotation of the disk with reference to the brush.

50 In accordance with the present invention it is proposed to provide for more positively, accurately and uniformly predetermining the resistivity of the conductive coating of the disk, in ways enabling maintenance in

service of the preselected value of such resistivity and also enabling and facilitating quantity production of devices having similar operative characteristics.

55 In the accompanying drawing wherein is illustrated an embodiment which the invention may assume in practice,

Figure 1 is a perspective view of such a device together with an associated instrumentality.

60 Figs. 2 and 3 are detail views illustrating more fully certain elements of Fig. 1.

Figs. 4 and 5 are detail views illustrating more fully other features of Fig. 1; while,

65 Figs. 6 and 7 are detail views illustrating a slight modification of the element shown in Figs. 4 and 5.

70 As illustrated, particularly in Figs. 4 to 7, inclusive, it is herein proposed to specially prepare or treat the peripheral surface of insulating disk 10 in ways adapting the same 75 to receive and permanently retain definite reduced quantities of conductive material throughout unit lengths of the current path about said disk, such quantities of the conductive material to be maintained from material of the brush 16 and to be originally supplied and applied either from said brush or in another preferred manner.

80 To such end it is proposed to provide the circumferential surface of said disk with a 85 plurality of regular and relatively fine grooves extending in directions having a circumferential and also an axial component. Such circumferential component is of importance in providing circumferential continuity of the groove, and of the conductive material therein, whereas the axial component is desirable for purposes of distributing and equalizing abrasion upon the coating 90 surface of the brush.

95 From the foregoing it results that, through predetermination and control of the number and size of the circumferentially continuous grooves provided, the resistivity of the conductive path about the disk and also of 100 unit lengths of such path may be very accurately predetermined and controlled. Also, by the aforescribed expedients quantity production of devices having uniform corresponding ohmic and other characteristics 105 is enabled and facilitated.

The aforescribed grooves may in practice assume different forms, such for ex-

ample as the continuous spiral illustrated at 10 and 10^b in Figs. 4 and 6 or the cross hatched form shown at 10^a and 10^c in Figs. 5 and 7 in which latter forms the current is transmitted through a multiplicity of zig-zag paths. Also the grooves may be applied to a disk having straight edges as in Figs. 6 and 7 or having curved edges as in Figs. 4 and 5. The aforescribed disk may comprise hard rubber or other preferred insulating material whereas in practice the same is preferably rigidly secured upon a suitable operating shaft 11 which is rotatably mounted within axially spaced supports comprising an insulating block or board 12 and a conductive strip 13 suitably secured thereto. Said conductive strip is preferably provided with a suitable external terminal device and is utilized to provide for external electrical connection of said operating shaft or a part in electrical connection therewith. A spring washer 14 is preferably interposed between the disk and conductive supporting strip to provide for firm and resilient engagement between the conductive supporting strip 13 and an enlarged head 15 of said operating shaft.

Brush 16 is carried by a suitable holder, which may preferably comprise an elongated metallic block 17 having a transverse bore or passage to receive said brush and also having reduced and threaded opposed terminal portions adapted to receive suitable conductor clamping nuts, as illustrated. One of the terminal portions of said block is adapted to penetrate the insulating board 12 for securing of the brush holder to the latter whereas a spring clip 18 is carried by the other of said terminal portions for forcing the brush into positive contact with the periphery of disk 10.

As a convenient means for electrically connecting and physically supporting the device with reference to an associated instrumentality a stiff but flexible supporting jumper 19 may be provided. Said jumper is provided with a suitable eye for direct securing to a terminal of the associated device, and is further provided at its opposite end with another eye for direct securing to the last mentioned terminal portion of block 17. Said eyes may be angularly displaced with reference to one another. Said jumper is further provided with an out-

55 struck lug portion 20 adapted to co-act with an edge portion of the insulating support 12 to assist in supporting and permanent positioning of the device. The aforescribed construction and arrangement, including flexibility of said jumper thus provide for permanent mounting of the device in practically any desired relation to the associated instrumentality.

56 In practice the operating shaft may be provided with an adjustable insulated extension as shown.

What we claim as new and desire to secure by Letters Patent is:

1. In a variable resistance device, the combination with relatively movable resistor and contactor elements each comprising relatively soft material, of an insulating support for said resistor to co-act with said contactor, said support having continuous grooves, to contain material of said resistor, and intermediate ridges to effect abrasion of said contactor.

2. In a variable resistance device, the combination with relatively movable resistor and contactor elements each comprising relatively soft material, of an insulating support for said resistor to co-act with said contactor, said support having continuous grooves, to contain material of said resistor, and intermediate ridges to effect abrasion of said contactor, said grooves and ridges extending in directions having a component parallel to the direction of relative movement of said resistor and contactor.

3. In a variable resistance device, the combination with relatively movable resistor and contactor elements each comprising relatively soft material, of an insulating support for said resistor to co-act with said contactor, said support having continuous grooves, to contain material of said resistor, and intermediate ridges to effect abrasion of said contactor, said grooves and ridges extending in directions having a component parallel to the direction of relative movement of said resistor and contactor, and also having a component angularly related to such direction.

In witness whereof, we have hereunto subscribed our names.

HENRY J. WIEGAND.
HORACE N. PACKARD.
